CLIO B. YAW, OF ARLINGTON, NEW JERSEY, ASSIGNEE TO REMINGTON TYPEWRITER COMPANY, OF ILION, NEW YORK, A CORPORATION OF NEW YORK.

TYPE-WRITING MACHINE.

1,198,503.

Specification of Letters Patent. Patented Sept. 19, 1916.

Application filed June 9, 1916. Serial No. 102,642.

To all whom it may concern:

Be it known that I, Clío B. Yaw, citizen of the United States, and resident of Arlington, in the county of Hudson and State of New Jersey, have invented certain new and useful Improvements in Type Writing Machines, of which the following is a specification.

My present invention relates to ribbon mechanism for typewriting machines, and more especially to novel devices for controlling the vibratory movements of the ribbon and for feeding it, and the principal objects of the invention are to provide improved devices of the character specified.

To the above and other ends my invention consists in the features of construction, combinations of devices and arrangements of parts hereinafter described and particularly pointed out in the claims.

In the accompanying drawings which illustrate the preferred form of my invention, Figure 1 is a fragmentary front to rear vertical sectional view of a typewriting machine embodying my invention. Fig. 2 is a fragmentary rear elevation partly in section of said machine. Figs. 3 and 4 are details of a ribbon carrier spool. Fig. 5 is a fragmentary front elevation of the upper part of said machine. Fig. 6 is a fragmentary perspective view showing parts of the ribbon vibrating and controlling mechanism. Figs. 7 and 8 are details of the ribbon reversing mechanism.

Referring to Figs. 1, 2 and 5, the main frame of the machine, comprising a base portion 1 and uprights 2 which support a top plate 3, has at its rear a fixed trackway 4 which coöperates through anti-friction balls 5 with the slide bar 6 of a carriage, which further comprises end bars 7 that pivotally support a platen frame 8 on which is mounted a cylindrical platen 9. The carriage and platen are constantly urged leftward by a spring drum 10, which is connected to the carriage by a toothed wheel 11 that turns with the spring drum and meshes with a rack bar 12 on the slide bar 6. Step-by-step leftward movements of the carriage are controlled by escapement devices comprising a pinion 13 that meshes with a set of teeth on the rack bar 12, and is mounted on a shaft 14 which carries at its lower end a toothed escapement wheel which coöperates with escapement dogs that are actuated from

the printing keys. The escapement wheel and dogs are not illustrated herein but are preferably of the character fully disclosed in my co-pending application Ser. No. 855,551, filed August 7, 1914. Cooperative with the front face of the platen 9 are a series of ball bearing type bars 15 having a stationary fulcrum 16 and each connected by a link 17 with a lever 18 fulcrumed at 19 on a stationary support 20, the tail portion 18^a of each lever being connected to a restoring spring 21. A link 22 connects each lever 18 with one arm of a bed crank 23, the other arm whereof is connected to an upright key stem 24 provided with a key-clip 25, said key stem bearing in a plate 26 fixed to the main frame. A curved universal bar frame 27 which is vertically arranged in rear of the type bars is operative by the tails 18^a of the levers 18. The universal bar frame which is supported and guided by crank arms 28 on a rock shaft 29 is connected by devices not shown to operate the escapement dogs aforesaid.

Referring next to the ribbon feeding mechanism, the ribbon 30, which may be longitudinally divided into the usual fields "a" and "b" of different colors or characteristics, is wound on wooden core pieces 31 (Figs. 1, 2, 3 and 4), the ends of the ribbon being secured to the core pieces by spring clips 32. These core pieces fit over the upper ends of vertical shafts 33 which take bearing in the top plate and also in lugs or brackets 34, projecting inward from the sides of the base, said shafts being arranged one at each side of the machine and somewhat forward of the printing face of the platen. Near the upper end of each shaft 33 is fixed a flanged collar 35 from which projects upward a vertical pin 36 that engages with a hole indicated at 37 in the core piece so that the latter is forced to turn with its supporting shaft. Underlying the core piece is a loose flange or bottom piece 38 which also is perforated for the passage of the pin 36. The inner plies of the ribbon are supported by said flange 38. During rotary feeding movements the flange 38 turns in the bottom of a fixed cup or housing 39 for the wound portions of the ribbon, each cup being supported on short posts 40 rising from the top plate. The bottom of the cup is formed with a circular cut-out indicated at 41 of slightly less diameter than the flange 38. Each cup is provided with a cover or top 42, which fits into and

frictionally engages the cup. The inner side of each cup is formed with a slot or cutaway 43 for the passage of the ribbon as it winds off and on the core pieces. These 5 core pieces 31 together with the loose flanges 38 constitute ribbon carriers which are readily removable from their cups or housings. Fixed to the lower end of each shaft 33 is a beveled pinion 44 which is adapted 10 to mesh with a corresponding beveled pinion 45, the pinion 45 being mounted on the horizontally disposed ribbon driving or power shaft 46, which takes bearings in the sides of the base and at the right-hand side 15 projects through the base and is provided with a turning handle 47. The power shaft carries an elongated pinion 48 which meshes with a spiral gear 49 fixed to the lower end of an oblique shaft 50 that inclines upward 20 and rearward, taking bearings in a stationary bracket 51. The upper end of the shaft 50 is provided with a pinion 52 which meshes with the toothed wheel 11 thus connecting the shaft 46 with the spring drum 25 10. Fixed to the shaft 50 is a ratchet wheel 53 which is engaged by a spring detent 54 that prevents backward rotation of the shaft 50. The pinion 48 and the gear 49 are constantly in mesh but provision is made for 30 turning the shaft 46 by the handle 47 without affecting the shaft 50, this being accomplished by mounting the pinion 48 loosely on the shaft 46 and providing one end of said pinion with a set of ratchet teeth 55 with 35 which engages a corresponding ratchet 56 that is integral with a clutch member 57 slidably mounted on the shaft 46 and engaged by a coöoperating clutch member 58 fixed to the shaft 46. The ratchets 55 and 40 56 are maintained engaged by a coiled spring 59 that is arranged between the ratchet and the hub portion of the clutch member 58. When the handle 47 is turned the shaft 46 will turn, this turning movement being transmitted through the clutch member 58 to the clutch member 57 whose ratchet 56 will click over the ratchet 55. When motion is transmitted in the opposite direction, however, from the shaft 50 to the 45 50 shaft 46, the ratchet 55 will force the ratchet 56 to turn with it, thus forcing the shaft 46 to turn.

The driving pinions 45 are so disposed on the shaft 46 that only one of said pinions at 55 a time can coöperate with its associate pinion 44 as is usual, and by shifting the shaft 46 endwise the pinions 45 may be alternately connected and disconnected in turn, thus reversing the ribbon feed. During 60 such shifting the elongated pinion 48 will always remain in engagement with the spiral gear 49. The shafts 33 are preferably spring mounted, coiled springs 33^a being interposed between the brackets 34 and the hub portions of the pinions 44. These springs tend

constantly to press the shafts 33 downward and maintain the hub portions of the flange members 35 in contact with the top plate 3. The endwise shifting of the shaft 46 may be accomplished by hand through pushing or pulling on the handle 47, or else by automatic shifting or reversing devices next to be described. Said shaft is maintained in one or the other of its shift positions by detent devices of ordinary construction 70 enclosed in a housing 60 secured to the right-hand side of the main frame. 75

The ribbon reversing mechanism comprises angular reversing members 61 arranged within slots cut in the upper ends of the shafts 33. Each reversing member is pivotally connected at 62 to the upper end of a rod 63 that is slidably mounted in a hole extending longitudinally through the shaft 33. The lower end of each rod is 80 adapted to engage with an underlying worm 64 on the end portion of the shaft 46 to move said shaft endwise to reverse the ribbon. As hereinafter described the rods 63 may be alternately raised and lowered to 85 effect this result. Each reversing member 61 comprises an upright arm 61^a which is adapted to play in a slot 65 cut in the core-piece 31, the flange 38 also being notched at 66 to allow of such play. The horizontally disposed arm of the reversing member 61 terminates at one end in a toe portion 61^b to contact with the flange 35, which acts as an abutment or fulcrum for the member 61. The opposite end of said horizontal 90 portion terminates in a projection 61^c. Normally the upright arm 61^a is confined within the slot 65 by the folds of the ribbon as shown in Fig. 2, and as a result the rod 63 is lifted so that its lower end is clear of its 95 associate worm 64. When the ribbon has been completely unwound from the core piece, however, the member 61 will swing out and down until it is arrested by the flange 35 as shown in Fig. 7, causing a lowering of the rod 63 until it engages with the underlying worm, with the result that as 100 turning movements of the shaft 46 continue, said shaft will be wormed along endwise until the pinion 44 adjacent the lower 105 rod 63 is engaged by the associate pinion 45, the pinion 45 at the opposite end of the shaft 46 being concurrently disengaged or rendered inoperative. As thereafter the shaft 33 and its lower rod 63 continue to 110 turn the projection 61^c will come in contact with a cam piece 67, Figs. 2 and 8, screwed fast to the top plate in the path of said projection, with the result that the member 61 will be cammed or swung upward about the 115 toe 61^b as a center lifting the rod and restoring the upright portion 61^a within the slot where it will be confined by the first ply of the winding-on ribbon. From what has 120 been said it is believed that it will be clear 125 130

that the direction of feeding movement of the ribbon will be automatically reversed each time the ribbon is completely unwound from one of the carriers and wound on the other carrier.

Referring now to the mechanism for vibrating the ribbon at printing operation and to the field-changing mechanism for controlling the extent of such vibration so as to vary widthwise the printing portion of the ribbon exposed to the types, which mechanism involves novel features, reference may be had to Figs. 1, 2, 5 and 6. In its passage from one ribbon carrier to the other across the front of the platen and below the printing line thereon the ribbon is threaded through a vibratory ribbon carrier or vibrator 68 which is preferably of sheet metal and comprises a vertically disposed head 69 provided with two diagonally arranged guide loops 70 terminating at their free ends in horizontally disposed portions 70^a. Said vibrator further comprises a rearwardly and downwardly extending stem portion 71 which passes through a cut-out 72 in the top plate 3. Across the cut-out and above the same is arranged a bridge-piece 73 which is attached to the upwardly extending part of the top plate and serves as a stop for the vibrator in its movements to printing position. The rear end portion of the stem of the vibrator is secured by screws 74 to the inner end of a rock shaft 75, the end portion of said shaft being cut off to provide a flat seat for the stem, the vibrator 68 and the rock shaft 75 together constituting a single rigid member. The rock shaft bears in a tube 76 which extends leftward back of and slightly below the top plate and its outer or left-hand end is driven into or otherwise fixed in a block or hub-piece 77 which is also perforated to afford passage for the rock shaft, which projects leftward therethrough. Said hub-piece in turn is fixed to the rear end of a rod or rock shaft 78. The rock shaft is arranged at right-angles to the tube 76 and rock shaft 75, its rear end portion just forward of the hub piece 77 bearing in a stationary bracket 79 depending from the top plate 3, while its forward end portion bears in a lug 80 depending from the forward portion of the top plate near its left-hand side. The rock shaft 78 is adapted to be controlled by hand for purposes hereinafter explained and to that end is provided near its forward end with a crank arm 81, extending horizontally leftward, the outer end portion 81^a of said crank arm being bent forward at right-angles and passing through a notch or slot in the left-hand end portion of the front shield 82. The portion 81^a is provided forward of said shield with a key or finger button 83 that has on it indicating marks.

For example, the upper and lower halves of

said button may be colored to correspond respectively to the upper and lower fields "a" and "b" of the ribbon 30. Detent devices are provided for holding the crank arm 81 and the parts that it controls in set positions, said detent devices comprising a lever member 84 pivoted to the front of the crank arm 81 at 85. The left-hand end of said lever member is notched as indicated at 86 to embrace the portion 81^a of the crank arm 75 while the right-hand arm of said member terminates in a pointed or beveled portion 87. This pointed portion co-operates with the free end of a spring detent 88 which is properly shaped for such co-operation, the lower end of said detent being secured by screws 89 to a lug 90 on the rear of the shield 82.

The parts heretofore described comprising the tubular bearing 76, hub 77, rock shaft 78, crank arm 81, key 83 and detent devices are provided for the purpose of controlling the normal position of the vibrator 68 and its rock shaft 75 so as to vary the printing portion of the ribbon exposed to the types or in the present instance to present either the ribbon field "a" or the ribbon field "b" opposite the printing point "p" of the platen. In other words, they constitute ribbon field-changing mechanism. In order to vibrate the ribbon at printing operation, connections are provided for rocking the shaft 75 by actuation of the printing keys, said connections comprising a crank arm 91 having a hub 92 fixed to the rock shaft 75 outside the hub 77. The crank arm 91 extends horizontally forward and has pivotally connected to it the upper end of a link 93, said link extending vertically downward and being curved forward at its lower end where it is pivotally connected at 94 to the free end of a crank arm 95 which is fixed to and extends horizontally forward from the rock shaft 29 near the left-hand end thereof. The construction is such that when a printing key 25 is actuated and the shaft 29 is rocked as heretofore explained, the crank arm 95 will thereby be swung upward, raising the link 93 and swinging the crank arm 91 upward, rocking the shaft 75 in its bearing 76 and swinging the vibrator upward and rearward. This swinging movement of the vibrator carries it from a position somewhat forward of the platen and below the printing point to a position where it will contact with the bridge 73 and present opposite the printing point "p" the printing portion of the ribbon that extends between the two loops 70. When the parts are positioned as illustrated in Figs. 1, 2 and 5, this vibratory movement communicated to the vibrator by actuating devices will swing it so as to present the upper ribbon field. It will be understood that during this vibratory movement of the ribbon,

130

the bearing 76 and the connections thereto comprising the rock shaft 78 and crank arm 81 will not be affected. These parts remain set in fixed position under control of the devices 84 and 88. When it is desired to dispense with the use of the upper field "a" and to switch to the ribbon field "b", or lower field, the button 83 is pressed down from the full-line position shown in Figs. 2 and 5 to the dotted line position shown in said figures, and this will have the effect of swinging down the crank arm 81 and swinging up the inner arm of the lever 84 so that its pointed end 87 will coöperate with the upper end of the spring detent 88 to hold the crank arm 81 in its lower position. The downward swing of the crank arm 81 will correspondingly rock the shaft 78 which in turn will rock the hub 77 and swing the tubular bearing 76 upward about the axis of the rock shaft 78 as a center, as indicated by dotted lines in Fig. 2. As a consequence the rock shaft 75 within said bearing 76 will be similarly swung upward about the axis of said rock shaft 78, and the vibrator 68 at the inner free end of said rock shaft will be moved upward and rearward from the normal position shown in full lines in Fig. 1 to the normal position indicated by dotted lines in said figure. This change in the normal position of the vibrator and its controlling devices will not affect the vibrator actuating devices comprising the link 93 and crank arm 95, there being sufficient looseness at the point of connection of the link 93 with the crank arm 91 to allow of this, the swinging movement of said crank arm 91 about the axis of the rock shaft 78 being comparatively slight. In this field-changing operation it will be observed that parts 76, 78 and 81 operate as a single lever member having an elongated fulcrum portion. In order positively to limit the swinging movements of the tube 76 stop devices are preferably provided for coöperation with the inner end portion of said tube, said stop devices comprising a bracket 96 fixed to the rear portion of the top plate by screws 97 and provided with rearwardly extending lugs 98 and 99 spaced apart to allow sufficient play of the tube 76 which is arranged between them. The lower lug 98 provides a stop for the tube when it is in its lower position while to insure accuracy of adjustment the upper lug 99 is preferably provided with an adjustable screw stop 100 which arrests the tube when it is swung upward to raise the vibrator to its upper normal position. The stop 73 limits vibratory movements of the ribbon vibrator.

It will be observed that by my present invention I provide in combination with a ribbon vibrator, ribbon field-changing devices or mechanism which comprise a pivotal support for said vibrator, and means

for communicating pivotal movement to said support to change the normal position of said vibrator, in order to change the field of the ribbon that is presented to the types when the vibrator is actuated; that in the present instance the pivotal support is in the form of a tubular bearing, which is rigid on a rock shaft, that is key-controlled from the front of the machine by a key that is rigid with said rock shaft, said rock shaft being mounted on an arm that extends radially therefrom, said tubular bearing also projecting rearward from said rock shaft; that the ribbon vibrator is rigidly connected to a pivotal device or rock shaft which takes bearings in said tubular bearing; that the ribbon vibrating devices in the present instance comprise a vibrator proper and a rock shaft on which said vibrator is fixed; that said rock shaft bears in a tube which is rigid on the second rock shaft; that the second rock shaft remains quiescent when the first rock shaft is rocked to move the vibrator to and from the printing point; that said first rock shaft does not rock on its own axis when the ribbon field is charged but does turn about a center which is coincident with the axis of said second rock shaft, in other words the rock shaft is moved pivotally about an axis which is at an angle to the pivotal axis of the rock shaft itself; and that the first rock shaft has one arm fixed to it, *i.e.*, the vibrator proper which carries the ribbon, and another arm fixed to it which is connected to vibrating devices operative from the printing keys.

My present invention provides for an exceedingly simple and effective ribbon field-changing mechanism, the parts being few and not liable to get out of order and the construction being such that the chance of overthrow is minimized.

Various changes may be made without departing from my invention.

What I claim as new and desire to secure by Letters Patent, is:—

1. In a typewriting machine, the combination of a ribbon vibrator, a pivotal device to which said vibrator is rigidly connected, means for moving said pivotal device predetermined extents to change the normal position of said vibrator, and means connected to said pivotal device for vibrating said vibrator, the last recited means remaining quiescent when the change in normal position of the vibrator takes place.

2. In a typewriting machine, the combination of a ribbon vibrator, a pivotal device on which said vibrator is mounted, a bearing in which said pivotal device bears, means for moving said bearing to change the normal position of said vibrator, and vibrating means connected to said vibrator.

3. In a typewriting machine, the combination of a ribbon vibrator, a pivotal de-

vice to one end of which said vibrator is fixed, a bearing in which said pivotal device bears, vibrating devices connected to the other end of said pivotal device, and 5 means for moving said bearing to change the normal position of said vibrator.

4. In a typewriting machine, the combination of a ribbon vibrator, a pivotal device to one end of which said vibrator is fixed, a bearing in which said pivotal device bears, vibrating devices connected to the other end of said pivotal device, and means for moving said bearing to change the normal position of said vibrator, the 10 15 vibrating devices remaining quiescent when said means is operated.

5. In a typewriting machine, the combination of a ribbon vibrator, a pivotal device to which said vibrator is connected, means 20 for communicating pivotal movement to said device at an angle to its own pivotal axis, and means for communicating pivotal movement to said device about its own pivotal axis as a center.

25 6. In a typewriting machine, the combination of a ribbon vibrator, a pivotal device to which said vibrator is connected, means for communicating pivotal movement to said device at an angle to its own pivotal axis, and means for communicating pivotal movement to said device about its own pivotal axis as a center, both said means being hand controlled independently of each other,

35 7. In a typewriting machine, the combination of a ribbon vibrator, a pivotal device to which said vibrator is connected, means for communicating pivotal movement to said device at an angle to its own pivotal axis, and means for communicating pivotal 40 movement to said device about its own pivotal axis as a center, one of said means operating to change the normal position of the vibrator, and the other of said means operating to vibrate said vibrator at printing 45 operation.

8. In a typewriting machine, the combination of a ribbon vibrator, a rock shaft by which said vibrator is supported, means for rocking said shaft, a bearing for said shaft, 50 and means for moving said bearing to predetermined positions to vary the normal position of said vibrator.

9. In ribbon mechanism for typewriting machines, the combination of a rock shaft, 55 an arm fixed thereto and carrying the ribbon, another arm fixed to said rock shaft, vibrating devices connected to said other arm, and means for changing the normal position of said rock shaft.

60 10. In ribbon mechanism for typewriting machines, the combination of a rock shaft, an arm fixed thereto and carrying the ribbon, another arm fixed to said rock shaft, 65 vibrating devices connected to said other arm, a tubular bearing in which said rock

shaft bears, and means for moving said bearing predetermined extents.

11. In ribbon mechanism for typewriting machines, the combination of a rock shaft, 70 an arm fixed thereto and carrying the ribbon, another arm fixed to said rock shaft, vibrating devices connected to said other arm, a tubular bearing in which said rock shaft bears, and a second rock shaft by which said tubular bearing is supported. 75

12. In ribbon mechanism for typewriting machines, the combination of a rock shaft, an arm fixed thereto and carrying the ribbon, another arm fixed to said rock shaft, 80 vibrating devices connected to said other arm, a tubular bearing in which said rock shaft bears, and a second rock shaft by which said tubular bearing is supported, hand controlled means for moving said second rock shaft predetermined extents, and 85 detent devices for maintaining said second rock shaft in set positions.

13. In a typewriting machine, the combination of a ribbon vibrator, a rock shaft by which said vibrator is supported, a bearing 90 for said rock shaft, a second rock shaft by which said bearing is supported, means for actuating said second rock shaft, and means for actuating said first recited rock shaft.

14. In a typewriting machine, the combination of a ribbon vibrator, a rock shaft by which said vibrator is supported, a bearing for said rock shaft, a second rock shaft by which said bearing is supported, means for actuating said second rock shaft, and means 100 for actuating said first recited rock shaft, both means being operated independently of each other.

15. In a typewriting machine, the combination of a ribbon vibrator, a pivotal support therefor, means for communicating pivotal movement to said support to change the normal position of said vibrator, stop devices for limiting the pivotal movements of said support, detent devices for maintaining 110 said support in set positions, and means for actuating said vibrator at printing operation.

16. In a typewriting machine, the combination of a ribbon vibrator, a pivotal device 115 on which said vibrator is mounted, a bearing in which said pivotal device bears, means for moving said bearing to change the normal position of said vibrator, stops for limiting the movements of said bearing, 120 detent devices for maintaining said bearing in set positions, and vibrating means connected to said vibrator.

17. In a typewriting machine, the combination of a ribbon vibrator, means for actuating 125 said vibrator at printing operation, ribbon and changing devices comprising a hand operated crank arm and detent devices for said field changing devices, said detent devices comprising a lever member 130

- 5 pivoted to said crank arm and provided with means for limiting its pivotal movement thereon, and comprising also a spring detent with which said lever member co-
6 operates.
18. In a front-strike typewriting machine, the combination of a platen, a ribbon vibrator, a rock shaft with which said vibrator is connected, said rock shaft extending
13 lengthwise of the platen, a bearing for said rock shaft, a second rock shaft to which said bearing is connected, said second rock shaft extending forward at right-angles to the platen axis, a field-changing key connected
15 to said second rock shaft, and printing keys operative on said first recited rock shaft.
19. In ribbon field-changing mechanism for typewriting machines, the combination of a key controlled rock shaft, a bearing
20 rigid therewith, and a ribbon vibrating device mounted in said bearing.
20. In ribbon field-changing mechanism for typewriting machines, the combination of a key controlled rock shaft, a tubular
- 25 bearing fixed to said rock shaft at substantially right-angles thereto, and a ribbon vibrating device in said bearing.
21. In ribbon field-changing mechanism for typewriting machines, the combination of a rock shaft, a key rigidly connected to
30 said rock shaft and projecting radially therefrom, a bearing rigid with said rock shaft and projecting radially therefrom, and a ribbon vibrating device in said bearing.
35
22. In a typewriting machine, the combination of a vibrator, a swinging support therefor, stops for said support, and a stop for said vibrator.

Signed at the borough of Manhattan, city 40
